[57] CLAIM

The ornamental design for a switch plate with voice recorder, as shown and described.

DESCRIPTION

FIG. 1 is a front plan view of a switch plate with voice recorder, showing my new design;

FIG. 2 is a back plan view thereof;

FIG. 3 is a top view thereof;

FIG. 4 is a bottom view thereof;

FIG. 5 is a left side view thereof;

FIG. 6 is a right side view thereof;

FIG. 7 is an isometric front view thereof;

FIG. 8 is an isometric back view thereof;

FIG. 9 is a front plan view of an alternate embodiment of the invention;

FIG. 10 is an alternate embodiment back plan view thereof;

FIG. 11 is a top view of the alternate embodiment of FIGS. 9 and 10;

FIG. 12 is a bottom view of the alternate embodiment of FIGS. 9 and 10;

FIG. 13 is a left side view of the alternate embodiment of FIGS. 9 and 10;

FIG. 14 is a right side view of the alternate embodiment of FIGS. 9 and 10;

FIG. 15 is an isometric front view of the alternate embodiment of FIGS. 9 and 10; and,

FIG. 16 is an isometric back view of the alternate embodiment of FIGS. 9 and 10.
